COMBINED PEG, MAGNETIC AND CHALK BOARD

Wesley E. Sharer, Chicago, Ill., assignor to
Playskool, Inc., Chicago, Ill.

Filed Aug. 19, 1970, Ser. No. 24,576

Term of patent 14 years

Int. Cl. D19—08

U.S. Cl. D25—1

FIG. 1.

FIG. 2.

FIG. 3.

FIG. 4.

FIG. 1 is a front elevational view of a combined peg, magnetic and chalk board embodying my novel design; FIG. 2 is a rear elevational view thereof; FIG. 3 is an end elevational view thereof; and FIG. 4 is a top plan view thereof.

The bottom is identical to the side shown in FIG. 2. The end not shown is identical to that shown in FIG. 3.

I claim:

The ornamental design for a combined peg, magnetic and chalk board, as shown and described.
